(57) CLAIM

The ornamental design of a package for a newspaper, as shown and described.

DESCRIPTION

FIG. 1 is a top view of a package for a newspaper, showing my new design, the undisclosed bottom is not part of the claimed design;

FIG. 2 is a side elevation view thereof; and,

FIG. 3 is an end elevation view thereof.

The broken line showing the newspaper in the Figures is for illustrative purposes only and forms no part of the claimed design.
